(57) **CLAIM**

The ornamental design for a rectangular tile magnetic toy, as shown and described.

DESCRIPTION

FIG. 1 is a front, right and bottom perspective view of first embodiment of a rectangular tile magnetic toy, showing my new design;

FIG. 2 is a rear, right and bottom perspective view thereof;
FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is a front, right and bottom perspective view of second embodiment of a rectangular tile magnetic toy;

FIG. 10 is a rear, right and bottom perspective view thereof;
FIG. 11 is a front view thereof;

FIG. 12 is a rear view thereof;

FIG. 13 is a left side view thereof;

FIG. 14 is a right side view thereof;

FIG. 15 is a top plan view thereof; and

FIG. 16 is a bottom plan view thereof.

FIG. 17 is a front, right and bottom perspective view of third embodiment of a rectangular tile magnetic toy;

FIG. 18 is a rear, right and bottom perspective view thereof;

FIG. 19 is a front view thereof;

FIG. 20 is a rear view thereof;

FIG. 21 is a left side view thereof;

FIG. 22 is a right side view thereof;

FIG. 23 is a top plan view thereof; and

FIG. 24 is a bottom plan view thereof.

FIG. 25 is a front, right and bottom perspective view of fourth embodiment of a rectangular tile magnetic toy;

FIG. 26 is a rear, right and bottom perspective view thereof;

FIG. 27 is a front view thereof;

FIG. 28 is a rear view thereof;

FIG. 29 is a left side view thereof;

FIG. 30 is a right side view thereof;

FIG. 31 is a top plan view thereof; and

FIG. 32 is a bottom plan view thereof.

1 Claim, 32 Drawing Sheets
